(57) **CLAIM**

We claim the ornamental design for a splitable Y connector, as shown and described.

DESCRIPTION

FIG. 1 is a top perspective view of one half of a splitable Y connector engaging an identical other half of the splitable Y connector showing our new design;

FIG. 2 is a bottom plan view of the one half of the splitable Y connector shown in FIG. 1;

FIG. 3 is a top plan view of the one half splitable Y connector shown in FIG. 2;

FIG. 4 is a front elevational view of the splitable Y connector shown in FIG. 1;

FIG. 5 is a left elevational view of the splitable Y connector shown in FIG. 1;

FIG. 6 is a rear elevational view of the splitable Y connector shown in FIG. 1;

FIG. 7 is a right elevational view of the splitable Y connector shown in FIG. 1; and,

FIG. 8 is a top perspective view of the one half of the splitable Y connector shown in FIG. 2.
